WASHING APPARATUS

Karl K. Huppmann, Chicago, Ill., assignor to
 Walker Dishwasher Corporation, a corporation
 of Delaware

Application February 21, 1933, Serial No. 657,781

18 Claims. (Cl. 141—9)

My invention relates to washing apparatus, more particularly to apparatus for washing dishes, and has for its object the provision of improved apparatus of this character.

More specifically, my invention relates to dish-washing apparatus wherein a cleansing fluid, such as water, is circulated or hurled through the washing vat by suitable power means, such as a motor driven impeller. Certain dish-washing apparatus of this character heretofore in common use is provided with fluid inlet and drainage conduits communicating with the vat, and with an impeller driven by means of a motor arranged on the exterior of the vat and connected with the impeller by means of a shaft entering the vat.

In one of its aspects, my invention contemplates the provision in apparatus of this character of an improved arrangement of fluid inlet and drainage conduits, and of the impeller and its driving motor, whereby a more compactly and efficiently arranged organization of parts is secured.

In accordance with my invention, in one form thereof, the drain conduit communicates with the vat through a port in the bottom wall of the vat, and preferably, with the axis of the port substantially coaxial with the central vertical axis of the vat. The impeller is arranged to rotate above the drain port substantially in the vertical axis of the vat, and its driving shaft enters the vat through this port with its axis substantially coaxial with those of the port and vat. Surrounding the shaft is a valve controlling the drain port. The drain port and conduit preferably will be arranged in a suitable frame or bushing that is supported by the bottom wall of the vat, and this frame preferably will also be arranged to support the impeller driving motor and the shaft connecting the motor with the impeller.

In another form of my invention, not only are the impeller driving shaft and drain port arranged centrally of the vat substantially in its vertical axis, but the fluid inlet or supply conduit also is arranged to communicate with the vat substantially in this axis. In the preferred arrangement of this form, the fluid supply and drain ports are arranged about the impeller shaft substantially in concentric relation with each other. In this form, the fluid inlet conduit is arranged in the frame or bushing that serves to support the motor and shaft and in which the drainage conduit is provided.

For a more complete understanding of my in-

vention, reference should be had to the accompanying drawings in which Fig. 1 is a fragmentary view in elevation of dish-washing apparatus embodying my invention, portions being shown in section and portions being broken away so as to illustrate certain structural details; Fig. 1a is a fragmentary view in elevation illustrating a portion of the washing apparatus of Fig. 1; Fig. 2 is a plan view of a portion of the apparatus shown in Fig. 1, parts being shown in section and parts broken away so as to illustrate certain structural details; Fig. 3 is a fragmentary sectional view in elevation of dishwashing apparatus embodying a modified form of my invention; Fig. 4 is a fragmentary vertical central sectional view taken through a portion of the mechanism of Fig. 3; Fig. 5 is a view in plan of a portion of the apparatus of Fig. 3, parts being shown in section and parts broken away so as to illustrate certain structural details; Fig. 6 is a fragmentary sectional view in elevation of dishwashing apparatus embodying still another modified form of my invention; and Fig. 7 is a plan view of a portion of the apparatus of Fig. 6, portions being shown in section, and parts broken away so as to illustrate certain structural details.

In Figs. 1 and 2 of the drawings, I have shown my invention as applied to dishwashing apparatus comprising a vat 10 having a relatively deep chamber, preferably substantially square 30 in horizontal cross section. The walls defining the vat are formed of some suitable material, such as sheet metal, the surfaces of which may be enameled. The vat is supported in an upright position within and by means of a suitable casing (not shown). It will be understood that the vat is provided with a suitable cover (not shown).

It will also be understood that the vat will be provided with suitable dish supporting open- 40 work baskets or racks (not shown) which are removably supported in the lower and upper portions of the vat.

The bottom wall 12 of the vat 10 is provided with a plurality (four) of inclined portions 13 which slope downwardly toward the center of the vat and terminate in an opening 14 arranged centrally of the vat, the axis of the opening being substantially coaxial with the central vertical axis of the vat.

In the lower portion of the vat above the opening 14 is a suitable impeller 15 arranged to rotate on an axis substantially coaxial with the vertical axis of the vat and with the axis of the opening 14. The impeller 15 is operated by an 55

electric motor 16 mounted below the bottom wall of the vat. The motor shaft 16a enters the vat and has a driving connection with the impeller.

5 The motor 16 is supported on the bottom wall of the vat by means of a supporting frame 17. The four bottom walls 13 of the vat terminate in a circular inturned flange 20 surrounding the opening 14. The frame 17 is secured to this flange by means of a plurality of bolts (not shown) which are passed through a clamping ring member 21 supported on the upper side of the flange 20 and into tapped holes 20a provided for them in the frame 17.

10 15 As shown, suitable water-tight sealing means or gaskets 21a will be provided between the flange 20 and the frame 17 and the ring 21. The frame 17 is provided with a depending skirt 23 of enlarged diameter. This skirt serves to secure and

20 support the motor 16. As shown, the upper portion of the motor frame is provided with an outwardly projecting flange 24. This flange is received by a member 25 formed of some suitable resilient material, such as rubber. The resilient

25 member 25, as shown more clearly in Fig. 1a, has a plurality of spaced enlarged sections 25a of substantially U-shape and joined by U-sections 25b of somewhat smaller dimensions, the two legs of both U-sections 25a and 25b being arranged 30 to grip tightly the upper and lower sides of the flange 24. The resilient member 25 is secured within the skirt 23 by means of a clamping or pressure ring 26 which in turn is secured to the skirt by means of a plurality of radially disposed set screws 27 engaging the clamping member, as clearly shown in Fig. 1.

The frame 17, in addition to serving as a support for the impeller driving motor 16, has several additional functions: It serves to convey fresh 40 cleansing water to the vat 10, and further, serves to conduct soiled water from the vat to a suitable drain. The frame 17, as shown, is provided with an inlet or fresh cleansing fluid supply conduit 30. This passageway is defined by an outer wall 31 of the frame, an inner wall 36 spaced from the outer wall, a bottom wall 37 joining the inner and outer walls at the bottom, a top wall 38 joining these walls at the top and end walls 39 (Fig. 2). This passageway or conduit 30, as 45 shown (Fig. 2), extends along the periphery of one side of the frame through an arc that subtends an angle somewhat greater than 180°.

50 Communicating with this conduit 30 is a passageway or conduit 40, which, as will be pointed out hereafter in greater detail, communicates with a suitable source of fresh water supply.

The frame 17 is further provided with an internal chamber 41, one side of which is defined by the inner wall 36 of the conduit 30. Opposite 60 this wall the chamber is provided with a relatively long opening 42, which communicates with a conduit 43, which in turn communicates with a drain passageway 44. The top of the chamber opens into the vat through a port 41a. The bottom of the chamber is defined by a wall 45, which is provided with a central reentrant portion 46. This reentrant portion, as shown in Fig. 1, projects upwardly for some distance into the chamber 41 in a substantially vertical direction and 65 thence slopes inwardly toward the motor shaft 16a, finally terminating in a vertically arranged portion 47 of relatively small diameter. The portion 47, as shown, is provided with an aperture therethrough and supported in this aperture is 70 a sleeve 48 surrounding the motor shaft, arranged 75

in a substantially vertical position. The lower end of the tube 48 has a fluid-tight connection with the portion 47 of the bottom wall of the frame.

Surrounding this sleeve 48 is a valve 50 arranged to control communication between the vat and the drain chamber 41. This valve 50 is provided with a closure portion 51 that cooperates with a valve seat 52 supported by the frame 17. This seat, as shown, rests in a ledge 10 or recess provided for it in the frame. The valve is further provided with a sleeve 53 extending vertically upwardly from the closure portion and arranged in concentric and spaced relation with the sleeve 48. The space between the members 15 48 and 53 communicate directly with the drain chamber 41 and function as an overflow passage-way for the cleansing fluid or other liquid introduced into the vat 10.

15 The valve 50 moves vertically between its closed and open positions, and is guided in its movement on the sleeve 48 by means of a plurality of spaced guide members 54 that project inwardly from the sleeve portion 53 and slidably engage the outer surface of the tubular member 48. 20

25 A suitable valve operating member is provided, this member, as shown, comprising a horizontally disposed operating shaft 55 having a portion arranged within the drain chamber 41. This shaft is provided with crank arms 56 which carry outwardly projecting pins 57 that cooperate with arms 58 depending from the valve 50 and provided with apertures for receiving the pins, whereby the valve can be raised and lowered by rotating the shaft 55. 30

35 The shaft 55 protrudes from the chamber 41. The protruding portion of the shaft is operably associated with suitable operating mechanism. This operating mechanism forms no part of my invention, but is described and claimed specifically in a copending application of Carl M. Snyder and Jesse H. Clark, Serial No. 608,248, filed April 29, 1932 and assigned to the same assignee as this invention. As there described, the protruding portion of the valve operating shaft 55 is 40 provided with a crank arm 60 which is provided with a follower 61 that engages a suitable cam 62. The cam 62 is mounted on and moves with a shaft 63, which is geared to an operating shaft 64 through bevel gears 65. The shaft 64 is 45 provided with a suitable manually operable control member (not shown) whereby the motion of the cam shaft 63 and hence of the drain valve 50 is controlled. It is believed to be unnecessary to describe in further detail the means for operating the drain valve since, as previously pointed out, this specific operating mechanism forms no 50 part of my invention. 55

55 Arranged above the drain port 41a and valve 60 50 is a suitable strainer 66.

The impeller 15, as shown, is provided with blades 67 which may have any suitable shape, the important feature being that the blades be given a shape such that a cleansing fluid placed in the lower portion of the vat will be thrown upwardly 65 and outwardly through the dish supporting racks (not shown) in an efficient manner by rotary motion of the impeller.

70 The blades 67 of the impeller are mounted on an apron-like member 68 which, as shown, is provided with an enlarged skirt that is arranged exteriorly of the valve sleeve 53 and spaced from it sufficiently to avoid any possible interference by the valve to the rotation of the impeller or 75

by the impeller to the opening and closing movement of the valve.

The skirt of the apron-like member 68 tapers inwardly at its upper end where it is secured to the motor shaft 16a. As shown, the upper end of the skirt is provided with a reentrant portion 69 that surrounds and closely fits a bushing 70 secured to the motor shaft. The upper end of this bushing is provided with a flange 70a which, as shown, is received in a suitable recess provided for it in the upper end of the impeller. This bushing is secured to the shaft 16a by means of a screw 71, threaded into an aperture (not shown) provided for it in the motor shaft.

15 The impeller 15 comprising the blades 67 and their supporting apron 68 preferably will be formed as a single piece, and may be made from any suitable material, such as cast aluminum, or pressed steel.

20 The washing apparatus is provided with a suitable source of cleansing fluid supply, such as hot water, which is directed to the washing apparatus through a conduit 74. This conduit communicates with the conduit 40 and hence with the fluid supply conduit 30 through a suitable control valve 75. This valve comprises a closure member 76 that cooperates with a valve seat 77 which controls communication between the supply conduit 74 and the conduit 40. The valve seat divides the 25 valve housing into two chambers 78 and 78a, the former communicating with the supply passageway 74 and the latter with the conduit 40. The valve is provided with a piston 80 which is arranged to reciprocate in a cylinder 81, and which functions to operate the valve between its open and closed positions by means of fluid pressure which is admitted to the chamber 78 from the fluid supply conduit 74. Operation of the valve in response to this pressure is controlled by means 30 of a pilot valve 82 arranged axially of the valve and controlling communication between the cylinder 81 on the left of the piston and the chamber 78a. When the pilot valve is moved toward the left, as viewed in Fig. 2, pressure behind the piston is relieved and the fluid in the chamber 78 forces the inlet valve to the left thereby establishing communication between the conduit 74 and the passageway 40. When the pilot valve is returned to its right hand position, fluid leaking by the piston from the chamber 78 builds up a pressure behind it sufficient to close the valve.

45 The pilot valve is moved toward the left to effect the opening of the inlet valve 76 by means of a suitable lever 83 which in turn is controlled by means of a suitable cam 84 which operates the lever 83 through the medium of a pin or follower 85. The cam 84 is mounted on the shaft 53 with the drain valve cam 62 and hence is also operated by the manually operable control member (not shown) arranged to control the shaft 64. It is believed to be unnecessary to describe in further detail, the construction of the inlet valve or the mechanism for controlling its operation since these members form no part of my invention. 50 The inlet valve and its operating mechanism are described in detail and claimed in the above-mentioned copending Snyder and Clark application, Serial No. 608,248.

55 The supply chamber 30 communicates with the vat 10 through a suitable spray device, which as shown comprises a pair of upright conduits 81 and 88 disposed substantially 180° apart so as to be positioned on opposite sides of the impeller 15. These members are secured at their lower ends to upright coupling members 90 and 91 sup-

ported by the ring member 21 and which are in communication with the supply chamber 30 through nipples 92 and 93. Conduits 87 and 88 at their upper ends are turned inwardly toward each other at nearly right angles to the vertical, 5 and terminate in a chamber 94 arranged substantially in the vertical axis of the vat 10. Communicating with the chamber 94 is an upright conduit 95, and mounted for rotation on the upper end of this conduit and in fluid communication 10 with it is a suitable spinner or spray device 96. This spray device 96, as shown, is provided with a pair of reaction nozzles 97 and 97a. These nozzles are arranged at different angles to the vertical whereby the water issuing from them is 15 directed through different paths which sweep through substantially the entire upper portions of the vat and through the dish-supporting racks (not shown) supported in the vat.

20 The conduit 95 is provided on its exterior with 20 a plurality of radially disposed fins 98, which, as shown, slidably receive and guide a basket or tray 100 to a position of rest above the impeller and which function to secure the tray in the vertical position as shown in Fig. 1. 25

The spray device together with the arrangement of conduits 81, 88 and 95 conducting fluid to it are described and claimed in a copending application of Jesse H. Clark, Serial No. 653,243, filed January 24, 1933, and assigned to the same 30 assignee as this invention.

35 The impeller driving motor 16 is provided with a suitable source of electrical supply (not shown) controlled by means of suitable switching mechanism (not shown). This switching mechanism is controlled by suitable means comprising a cam 101 which also is mounted on the cam shaft 63 and controlled by the shaft 64. The control switching mechanism for the motor 16 forms no part of the present invention and it is believed 40 to be unnecessary, therefore, to describe it in detail. This mechanism, however, is described in detail and is claimed in the above-mentioned copending Snyder and Clark application Serial No. 608,248. As pointed out in this Snyder and Clark 45 application, in the operation of the washing apparatus the shaft 64 will be moved to various controlling positions for establishing a predetermined sequence of operation of the apparatus, which will include washing, and rinsing or spraying 50 cleansing steps. In one position of the shaft 64 both the inlet and the drain valves are opened whereby water from the supply source 74 is sprayed by the device 96 over the dishes and other articles to be cleansed and is passed directly to the drain 41, 43, 44. In another position of the shaft, the drain valve is closed while the inlet valve is opened so that water issuing from the spray device is allowed to accumulate in the vat. The water as it accumulates imposes a 55 load of increasing magnitude on the impeller 15. This increase in load is utilized to automatically close the inlet valve by mechanism described and claimed in the Snyder and Clark application. The shaft 64 of course is provided with an off 60 position. In this position, the drain valve is moved to its open position, the supply valve 76 is closed and the motor is deenergized.

65 It will be observed that I have provided an improved arrangement of fluid inlet and drain passageways 30 and 40, and 41, 43 and 44, which are incorporated in a single frame 17. This frame also serves to support the operating motor 16, and moreover, the valve mechanism controlling the inlet and drain conduits. The drain valve is ar- 75

ranged centrally of the vat and so also is the motor operating shaft 16a which enters the vat through the drain opening. The arrangement of parts, is therefore, very compact and efficient in construction.

In Figs. 3, 4 and 5, I have shown a modified form of my invention which is quite similar to the form shown in Figs. 1 and 2.

The vat 110 of the modified form is substantially circular in horizontal cross-section and is provided with an inverted frusto-conical bottom wall 111. In the lower portion of the vat and preferably arranged to be embraced by the bottom wall 111 is a suitable impeller 112 arranged to rotate on an axis substantially coaxial with the vertical axis of the vat. The impeller is driven by an electric motor 113 supported on the exterior of the vat and mechanically connected with the impeller by means of a shaft 114, arranged in the vertical axis of the vat.

The bottom wall 111 of the vat is provided with a centrally arranged circular opening 115 formed therein. In this opening is mounted a bushing 116 which serves to support the motor 113 and which, as will be pointed out in greater detail hereinafter, is provided with a drainage passageway for the vat. The bushing 116 is provided with a substantially horizontal annular flange 117 resting upon the inner surface of a suitable substantially flat supporting ledge 118 formed from the material of the bottom wall surrounding the opening 115. The bushing is also provided with a depending cylindrical portion 120 extending downwardly through the opening 115.

The bushing 116 carries a suitable frame 121 for supporting the impeller motor 113, this frame having an outwardly projecting flange or apron portion 122, to which the motor is detachably secured by suitable means, such for example as bolts 123 passed through suitable apertures 124 provided for them in the apron. Arranged above and below the apron are rubber insulating rings 125 and 126, the upper portion of the motor frame rests against the lower ring 126 and the heads of the bolts 123 rest on the upper rubber ring 125. The apertures 124 through which the bolts 123 are passed are enlarged somewhat as shown and the annular space about the bolts is filled with rubber insulation 127. The rubber rings 125 and 126 and the rubber 127 in the apertures serve to insulate the motor and provide a resilient mounting for it in the frame.

It will be observed that the frame 121 is provided above the apron with a cylindrical portion 128 which surrounds and fits rather closely the cylindrical depending portion 120 of the bushing 116. This portion 128 of the frame is detachably secured to the bushing by means of suitable clamping set screws 130 disposed circumferentially about the frame in spaced relation.

The frame 116 is provided with a drain chamber 131 communicating with the vat 10 through a port 132 and with a drain conduit 133 through a port 134. The conduit 133 preferably will be formed as a separate member and is detachably secured to the frame by means of screws 133a.

The chamber 131 has a bottom wall 135 generally inclined downwardly, as shown in Fig. 3, from one side of the drain port 132 to the drain 133 on the opposite side. This bottom wall is provided with a central reentrant portion 136 having a circular aperture 137 therethrough surrounding the motor shaft, the axis of the aperture being substantially coaxial with the vertical axis of the vat. Supported within this aperture

so as to extend in a vertical direction from the bottom wall 136 upwardly into the vat is a tubular member 138 corresponding to the tubular member 48 of the form shown in Figs. 1 and 2. Surrounding this tubular member is a valve 140 having substantially the same form as the valve 53 of Figs. 1 and 2. Thus, the valve 140 is provided with a valve closure portion 141 cooperating with the seat surrounding the drain port 132, and with a tubular portion 142 extending vertically upwardly therefrom and spaced somewhat from the tubular member 138 so as to provide an overflow passageway from the vat to the drain.

The valve 140 is operated between its closed and open positions, shown in full and dotted lines 15 in Fig. 3, by means of a shaft 141 which, as shown, projects into the chamber 131 and on its inner end carries a crank 143. This crank 143 is mechanically connected with the valve by means of a link 143a which is secured at one end to the 20 crank and at its other end to the valve portion 142, whereby the valve can be moved between its open and closed positions by rotating the shaft 141. The positions of the crank and link when the valve is closed are shown in dotted lines in 25 Fig. 3, whereas the positions of these members when the valve is open are shown in the dot-dash lines of Fig. 3. It will be understood that the shaft 141 will be provided with any suitable means (not shown) for operating it.

The impeller 112, as shown, is provided with an apron 144 which surrounds the valve 140 and is so proportioned that the valve has freedom of movement between its open and closed positions without any interference from the impeller and 35 so that the impeller has freedom of rotation without any interference from the valve. The apron 144 is secured at its upper end to the motor shaft 114. For this purpose, the apron is provided with a reentrant portion 145. This re- 40 entrant portion has a centrally arranged aperture therethrough, preferably of non-circular cross-section, which engages the upper end of the shaft 114 having a corresponding cross-section. The impeller is secured by means of a suitable 45 screw 146 threaded into the upper end of the motor shaft so that its head overlaps the adjacent edges of the impeller. The apron 144 supports the impeller blades 147 which, as shown, are arranged on opposite sides of the apron.

Water is introduced to the vat by means similar to the means for introducing the water of Figs. 1 and 2. In Fig. 3, however, the water is not supplied through a passageway provided in the drain conduit and motor supporting bushing 116, but 55 is introduced by means of a conduit 150 which communicates with a circular ring-like passageway or conduit 151 supported by the bottom wall of the vat substantially in a horizontal position. The circular conduit 151 communicates with a 60 plurality of conduits 152 similar to the conduits 87 and 88 of Figs. 1 and 2. There are four of these conduits 152 spaced substantially 90° apart and at their upper ends they communicate with a chamber 153 arranged in the vertical axis of 65 the vat. This chamber communicates with a vertical conduit 154 which in turn communicates with a spinner device 155 provided with reaction nozzles 156, 156a. The conduits 152 further serve to support a suitable open-work basket 157.

It will be observed that when the valve 140 is in its closed position the walls of the sleeve 142 of the valve 140 and the inner walls of the apron 144 of the impeller constitute a passageway leading from the interior of the vat to the drain. If 75

a flow of water be started through this passage-way, it is likely that the entire contents of the vat will be emptied by reason of siphon action. To avoid any possibility of siphon action, the apron 144 is provided with a plurality of apertures 158.

The apron 68 of Figs. 1 and 2 may also be provided with similar apertures, but in this apparatus there is very little likelihood of siphon action because the passageway to the drain defined by the apron, the valve 53 and the tubular member 48, is open at its upper end to the exterior of the vat through the interior of the tube 48; to the chamber between the frame 17 and the motor 16 defined by walls 46, 45, 37 and skirt 23, around the annular ring 25 between the resilient blocks 25a and between the motor and the annular clamping ring 26.

It will be understood that in operation of the apparatus when it is desired to spray or rinse the dishes, fresh water is supplied to the spray device through the conduit 150. Water issuing from the spray device is hurled through the dish supporting racks (not shown) and then finds its way to the bottom of the vat from which it is drained through the port 132 and passageways 131 and 133. The drain valve 140 will be opened, of course, for the spraying operation. When it is desired to wash the dishes, the drain valve is closed and the proper quantity of water is supplied to the vat where it accumulates in the bottom portion 111. The impeller 112 picks up the accumulated water and hurls it upwardly and outwardly through the dish supporting rack so as to effect a washing action on the dishes and utensils supported in them.

In Figs. 6 and 7, I have shown a still further modified form of my invention wherein water is admitted to the vat axially thereof. In this form of my invention, the vat 160 has substantially the same construction as has the vat 110 of Figs. 3 to 5. The bottom wall 161 of the vat 160 is provided with a centrally arranged opening 162 through which is supported a bushing 163. This bushing is provided with a flange 164 resting on the bottom wall of the vat and with a cylindrical portion 165 projecting downwardly through the vat. Arranged above this bushing is an impeller 166 which is driven by a motor 167 supported by the bushing 163 beneath the bottom wall of the vat in substantially the same fashion as is the motor 113 of Fig. 3 supported by its bushing 116. The motor 167 has a driving connection with the impeller by means of a shaft 168. The bushing 163 is provided with a drain chamber 170 communicating with the vat through a port 171 and with a drain conduit 172 through a port 172a. The arrangement of the drain chamber 170, the port 171, the conduit 172 and the port 172a is substantially the same as the arrangement of the corresponding parts of the form shown in Figs. 3 to 5. The drain chamber, as shown, is provided with an inclined bottom wall 170a similar to the bottom wall 135 of Fig. 3, the remaining walls of the chamber being formed as are the walls of Fig. 3. The port 171 is controlled by means of a valve 173 similar to the valve 140 of the form shown in Figs. 3 to 5. This valve is operated in substantially identically the same fashion as is the valve 140 of Figs. 3 to 5 by means of a shaft 174 mechanically connected with the valve through a crank arm 175 and a link 176. The impeller 166, like the impellers 15 and 112 of the previous forms described is provided with an apron 177 upon which the impeller blades 178 are supported. The apron 177 is provided with

apertures 178a arranged as are the apertures 158 of the impeller of Fig. 3 so as to prevent siphon action.

Fresh cleansing water is conducted into the vat axially thereof through an annular passageway 179 surrounding the shaft 168. This annular passageway is defined by a pair of tubular members 180 and 181 arranged in substantially concentric relation with each other and with the shaft 168 and supported by means of the bushing 163. 10 Water is supplied to the annular conduit 179 by means of a supply conduit 183. This conduit communicates with the annular passageway through a conduit 184, provided in the bushing 163. This chamber or conduit 184 is defined by 15 top and bottom walls 185 and 186 and by side walls 187 merging in the inclined bottom wall 170a of the drain chamber 170. As a matter of fact, the top wall 185 of the inlet passageway is defined by a portion of this bottom wall of the 20 drain passageway. The bottom wall 186 of the inlet chamber, as shown (Fig. 6) inclines upwardly from the conduit 183 and merges in the bottom wall 170a of the drain chamber substantially at the central vertical axis of the vat. 25

The bottom wall 170a of the drain chamber is provided with a reentrant portion 190 which is provided, as shown, with a centrally arranged aperture therethrough surrounding the shaft 168. The outer tubular member 181 is supported at its 30 bottom end in this aperture. The inner tubular member 180 is supported by the bottom wall 186 of the inlet passageway which is provided with a centrally arranged aperture 191 surrounding the shaft 168 and arranged to receive the lower 35 end of this tubular member. It will be observed that by reason of this construction, the inlet chamber 184 communicates directly with the annular passageway 179.

At its upper end the annular passageway 179 40 communicates with a spinner or spray device 193. The reaction nozzles 194 of the spinner are supported by means of a conduit 195 which at its lower end is supported by the impeller 166. The apron 177 of the impeller, as shown, is attached 45 at its upper end to the impeller shaft 168 by means of a member 196 which is fitted to the impeller shaft and secured thereto by means of a screw 196a. The member 196 preferably is formed integrally with the apron, but is spaced 50 somewhat from the apron and connected thereto by means of spaced radial arms 197. This arrangement provides for communication between the spray device and the annular supply conduit 179. Communication between the annular supply passageway 179 and the conduit 195 is established by means of a member 198 which is supported by the upper ends of the tubular members 180 and 181. This member 198 which preferably 55 will be formed of some flexible material, such as rubber, is provided with inner and outer portions 198a and 198b arranged, as shown, to be contracted about the inner and outer tubes 180 and 181 respectively. Between these inner and outer portions 198a and 198b is an annular passageway 60 or conduit 199 in direct communication with the supply passageway 179 and with the conduit 195. The inner and outer portions 198a and 198b are united at their upper ends by spaced 65 radial arms 200. The upper end of this member 70 198 lies against the inner walls of the apron 177 so as to establish a fluid-tight connection between the annular supply passageway 179 and the impeller. 75

It will be observed that fluid which is supplied 75

by the conduit 183 passes into the chamber 184 and thence to the annular passageway 179 from which it flows through the annular passageway 199 in the member 198 and thence into the conduit 195 to the spray device 193. The spray device of this form is carried by the impeller 166 as it rotates so that water which issues from the nozzles 194 is hurled in spray form through the vat.

10 Water drained from the vat by opening the valve 173 passes into the chamber 170 and from there flows into the drain 172.

While I have shown particular embodiments of my invention, it will be understood, of course, 15 that I do not wish to be limited thereto since many modifications may be made, and I, therefore, contemplate by the appended claims to cover any such modifications as fall within the true spirit and scope of my invention.

20 What I claim as new and desire to secure by Letters Patent of the United States is:

1. Dishwashing apparatus comprising walls defining a vat, the bottom wall of said vat being provided with a port providing for the passage of 25 liquid between the interior and exterior of said vat, a liquid circulating impeller within said vat above said bottom wall provided with an apron and liquid impelling blades carried by said apron, a driving shaft for said impeller entering said 30 vat through said port, a tubular valve closing said port surrounding said shaft in spaced relation with it and extending upwardly into said apron in spaced relation with said apron, a tubular member surrounding said shaft entering 35 said vat through said port spaced both from said shaft and said tubular valve, the upper end of said tubular member extending upwardly into said apron above the upper end of said tubular valve and opening into the interior of said vat 40 and the lower end opening to the exterior of said vat, and means for operating said valve between closed and open positions.

2. Dishwashing apparatus comprising a vat, 45 provided with a bottom wall having an opening therein, a drain, a frame below the bottom wall of said vat provided with walls defining a chamber closing said opening and having a port at its upper end communicating with said opening and a second port connecting the lower portion of 50 said chamber with said drain, the bottom wall of said chamber provided with a centrally arranged aperture, a fluid circulating impeller in said vat above said frame, a driving shaft for said impeller arranged vertically through said aperture 55 and directed into said vat through said chamber and said first named port, said first-named port having a diameter larger than the diameter of said shaft, a motor supported by said frame for operating said shaft, a valve for said first named 60 port surrounding said shaft, an operating member for said valve supported by said frame, said frame being provided with a fluid inlet passageway separate from said drain passageway, fluid conduits means between said fluid inlet passageway and said vat and a liquid sealing member 65 fitted into said aperture arranged to prevent the flow of liquid through said aperture when said valve is open to permit liquid to flow from said vat into said chamber.

70 3. Dishwashing apparatus comprising a vat provided with a bottom wall having an opening therein, a fluid circulating impeller in said vat above said opening, a frame below said bottom wall provided with bottom and side walls defining a chamber closing said opening and having a

port at its upper end communicating with said opening, a driving motor for said impeller supported by said frame on the exterior of said vat, a driving shaft operated by said motor directed vertically through said port at the upper end of 5 said chamber and said opening in the bottom wall of said vat, means connecting said shaft with said impeller, a valve for said port surrounding said shaft and controlling communication between said chamber and said vat, a tubular 10 member supported by said frame in position to extend vertically through said port and said opening in said bottom wall between said shaft and said valve, a liquid passageway from said chamber controlled by said valve, and a plurality of members on said valve engaging said tubular member so as to guide said valve in its movement between its open and closed positions.

4. Dishwashing apparatus comprising a vat 20 provided with a bottom wall having an opening therein, a frame supported below the bottom wall of said vat provided with a drain chamber having a bottom wall and a port at its upper end opposite said bottom wall communicating with said 25 opening in the bottom wall of said vat, the axis of said port being substantially coaxial with the vertical axis of said vat, the bottom wall of said chamber having a reentrant portion extending upwardly through said port and having an opening 30 therein arranged with its axis substantially coaxial with the vertical axis of said vat, a tubular member supported by said frame extending upwardly from said opening in said reentrant portion in a vertical position with its axis substantially coaxial with the vertical axis of said vat, an impeller in said vat provided with an apron 35 surrounding said tubular member and with fluid circulating blades carried by said apron, a motor for operating said impeller, a driving shaft between 40 said motor and said impeller directed through the opening in said reentrant portion of said bottom wall and through said tubular member, a tubular valve for closing said port surrounding said tubular member in spaced relation with it and having circumferentially spaced members 45 projecting inwardly so as to engage said tubular member to guide said valve between its opened and closed positions, and a drain conduit connected with said drain chamber. 50

5. Dishwashing apparatus comprising a vat provided with a bottom wall having a drain opening therein, a metallic frame, means supporting said frame below said bottom wall so as to close said opening, said frame being provided with a 55 passageway providing for the admission of cleansing fluid to said vat, and a centrally arranged passageway separate from and embraced by said first passageway providing for the drainage of soiled fluid from said vat, said centrally arranged 60 passageway communicating with said drain opening in the bottom wall of said vat, an impeller in said vat, a motor on the exterior of said vat for operating said impeller supported by said metallic frame, a shaft mechanically connecting said 65 motor with said impeller entering said vat through said centrally arranged drain passageway and a valve for said drain passageway surrounding said shaft arranged when closed to prevent the flow of liquid from said vat to said drain 70 passageway and when opened to permit liquid to flow from said vat to said drain passageway.

6. Dishwashing apparatus comprising a vat provided with a bottom wall having a drain opening therein, a metallic frame, means supporting 75

- 5 said frame below said bottom wall so as to close said opening, said frame being provided with a centrally arranged drain chamber communicating with said drain opening in said vat and constituting a drain passageway, and a second chamber arranged about said first mentioned chamber and constituting a fluid supply passageway for said vat, fluid conduit means connecting said fluid supply passageway with said vat, a fluid circulating impeller within said vat, a motor for driving said impeller supported by said frame, the shaft of said motor extending through said drain passageway and opening into said vat, means connecting said shaft with said impeller, a valve within said vat surrounding said shaft and arranged to control said drain opening and valve means carried by said frame arranged to control the supply of fluid to said fluid supply passageway.
- 10 20 7. Dishwashing apparatus comprising a vat provided with a bottom wall having an opening therein, a fluid circulating impeller in said vat, a frame supported below said bottom wall, said frame provided with bottom and side walls defining a chamber closing said opening and having a port at its upper end communicating with said opening and also with an opening in its bottom wall, a driving motor for said impeller supported by said frame on the exterior of said vat, a driving shaft operated by said motor directed through said opening in the bottom wall of said chamber, said port and said opening in the bottom wall of said vat, means connecting said shaft with said impeller, a tubular member having a diameter 25 larger than that of said shaft rigidly supported by said frame around said shaft with one end mounted in the opening in the bottom wall of said chamber and its other end communicating with the interior of said vat so as to define an open 30 passageway between the interior and the exterior of said vat, means providing a liquid-tight seal between said one end of said tubular member and said frame, a valve for said port surrounding said tubular member arranged in one position to close 35 said port to prevent the flow of liquid between said vat and said chamber and in another position to permit liquid to flow between said vat and said chamber and means supported by said frame controlling the operation of said valve.
- 40 50 8. Dishwashing apparatus comprising a vat, a drain, a frame at the bottom wall of said vat provided with bottom and side walls defining a drain chamber having a port at its upper end communicating with said vat and a port connecting the lower portion of said chamber with said drain, the bottom wall of said frame having a re-entrant portion shaped to direct liquid from said vat to said last named port, said reentrant wall portion having a centrally arranged aperture therein, a liquid circulating impeller in said vat above said frame, a driving shaft for said impeller arranged vertically within said aperture and directed through said drain chamber and said first named port into said vat, a motor supported by said frame for operating said shaft, a valve for said first-named port surrounding said shaft and an operating member for said valve supported by said frame.
- 60 70 9. Dishwashing apparatus comprising a vat, a metallic frame supported in the bottom wall of said vat provided with walls defining a centrally arranged drain chamber, said chamber having a bottom wall and a port connecting said chamber with said vat, a conduit in said frame communicating with said drain chamber and
- 75 adapted to be connected with a drain, said frame also being provided with walls defining a liquid supply chamber about said centrally arranged drain chamber and with a conduit communicating with said supply chamber adapted to be 5 connected with a liquid supply source, conduit means connecting said liquid supply chamber with said vat to convey liquid to said vat from said supply chamber, the bottom wall of said drain chamber having a centrally arranged aperture therein, an impeller in said vat above said frame provided with an apron and liquid impelling blades carried by said apron, a driving motor for said impeller secured to said frame beneath its bottom wall, the shaft of said motor 10 extending vertically through said aperture, drain chamber and port into said vat where it is connected with said impeller, a tubular valve closing said port to close said drain chamber to said vat surrounding said shaft in spaced relation with 15 it and extending upwardly into said apron, a tubular member fitted within said aperture and rigidly secured to said frame in an upright position within said tubular valve and in spaced relation with it, the upper end of said tubular member extending materially above said valve so as to provide a free fluid passageway between said vat and the exterior thereof, and means providing a liquid-tight connection between said tubular member and said frame around said aperture. 20 25 30 35 40 45 50 55 60 65 70 75 80 85 90 95 100
10. Dishwashing apparatus comprising a vat, a fluid circulating impeller in said vat, a driving shaft entering the bottom of said vat and having a driving connection with said impeller, walls defining a fluid inlet passageway for said vat arranged around said shaft, walls defining a fluid drain passageway for said vat around said fluid inlet passageway and a valve surrounding said walls defining said inlet passageway arranged to control said drain passageway. 40
11. Dishwashing apparatus comprising a vat provided with a centrally arranged drain port in its bottom wall, a drain passageway communicating with said port, a fluid circulating impeller in said vat, a driving shaft for said impeller entering said vat through said drain port, a fluid inlet passageway for said vat entering said vat through said drain port and a valve surrounding said shaft controlling said drain port. 45
12. Dishwashing apparatus comprising a vat provided with an opening in its bottom wall, a fluid circulating impeller in said vat above said opening, a frame below said opening having a drain passageway opening centrally into said vat, a motor supported by said frame, a shaft connecting said motor with said impeller entering said vat centrally of the opening of said drain passageway into said vat, said frame also having an inlet passageway terminating in said vat in an annular passageway surrounding said shaft and a valve for said drain opening surrounding said shaft and said inlet passageway. 55 60 65 70 75
13. Dishwashing apparatus comprising a vat having an opening in its bottom wall to provide for the drainage of liquid from said vat, a metallic frame below said vat provided with walls defining a chamber below said opening having an open upper end and a bottom wall opposite said open upper end, means securing said frame to said vat so as to close said opening in its bottom wall and so that the open upper end of said chamber communicates with said vat directly through said opening, said bottom wall of said chamber having an aperture therein, a fluid circulating impeller in said vat above said opening in its 75

- bottom wall, a vertically arranged drive shaft for said impeller extending through said aperture in said bottom wall of said frame chamber and directed upwardly through said chamber and into said vat through said opening in the bottom wall of said vat, a motor supported by said frame for operating said shaft, a tubular valve for said opening surrounding said shaft arranged when in one position to close said opening to said chamber to provide for accumulation of liquid in said vat and when in another position to open said opening to connect said vat directly with said chamber to provide for the drainage of liquid from said vat, an operating member for said valve supported by said frame arranged to move said valve between said positions, a tubular member mounted within said aperture in the bottom wall of said chamber extending upwardly through said chamber into said vat through said opening in its bottom wall about said shaft and within said tubular valve, means providing a liquid tight connection between said tubular member and said frame and a drain conduit connected with said chamber.
14. Dishwashing apparatus comprising a vat, a plurality of concentrically arranged fluid passageways communicating with said vat for conducting cleansing fluid to said vat and draining soiled fluid from said vat, a fluid circulating impeller within said vat, a driving shaft for said impeller directed into said vat through the inner of said passageways and a tubular valve within said vat controlling one of said passageways and surrounding said shaft.
15. Dishwashing apparatus comprising a vat, an impeller in said vat, a motor on the exterior of said vat for rotating said impeller, a shaft connecting said motor with said impeller, a fluid passageway surrounding said shaft, a tubular valve for said passageway surrounding said shaft and movable in the axis of said shaft between its open and closed position, and a second fluid passageway embraced by said valve communicating with said vat.
16. Dishwashing apparatus comprising a vat having a drain port in its bottom wall, a tubular valve for said port movable in a vertical direction between its opened and closed positions and hav-
- ing a portion extending vertically upwardly in said vat and constituting an overflow, a fluid circulating impeller in said vat arranged to rotate in the axis of movement of said valve having an apron-like portion embracing said upwardly extending portion of said valve and fluid impelling blades carried by said apron-like portion, a fluid inlet conduit entering said vat through said drain port and extending upwardly into said vat through said drain valve and said apron-like portion of said impeller and means connecting said inlet conduit with said vat at a point above said impeller.
17. Dishwashing apparatus comprising a vat provided with an opening in its bottom wall, a fluid circulating impeller in said vat above said opening, a frame below said opening having a drain passageway opening centrally into said vat, a motor supported by said frame, a shaft connecting said motor with said impeller entering said vat centrally of the opening of said drain passageway into said vat, said frame also having an inlet passageway terminating in said vat in an annular passageway surrounding said shaft, and a tubular valve for said drain opening surrounding said shaft and said inlet passageway extending vertically within said vat in spaced relation with said inlet passageway, the space between said valve and said inlet passageway communicating at the upper end of said valve with said vat and at the lower end with said drain passageway so as to constitute an overflow.
18. Dishwashing apparatus comprising a vat provided with an opening in its bottom wall, a fluid circulating impeller in said vat above said opening, a frame below said opening having a drain passageway opening centrally into said vat, a motor supported by said frame, a shaft connecting said motor with said impeller entering said vat centrally of the opening of said drain passageway into said vat, said frame also having an inlet passageway surrounding said shaft, concentrically arranged tubular members extending up into said vat within said impeller defining a passageway communicating with said inlet annular passageway and a tubular valve for said drain opening surrounding said tubular members.

KARL K. HUPPMANN.

CERTIFICATE OF CORRECTION.

Patent No. 2,022,637.

November 26, 1935.

KARL K. HUPPMANN.

It is hereby certified that error appears in the printed specification of the above numbered patent requiring correction as follows: Page 6, first column, line 64, claim 2, for "conduits" read conduit; page 8, second column, line 44, claim 18, for "a" read an annular; and line 45-46, claim 18, strike out the word "annular"; and that the said Letters Patent should be read with these corrections therein that the same may conform to the record of the case in the Patent Office.

Signed and sealed this 28th day of January, A. D. 1936.

Leslie Frazer

Acting Commissioner of Patents.
